LIP STICK HOLDER

John F. Babbitt, Louisville, Ky., assignor to J. V. Pilcher Mfg. Co., Inc., Louisville, Ky., a corporation of Kentucky

Application August 25, 1933, Serial No. 686,846

15 Claims. (Cl. 206—56)

An object of the invention is to produce a lipstick holder having a simple and efficient form of means for projecting and retracting the lipstick in relation to the container casing as a consequence of moving a closure member or cover away from, or back to its position over the open end of the casing.

Other objects will be clear from the accompanying specification and claims.

10 In the drawing

Figure 1 is a side elevation of the lipstick holder in closed condition, but showing in dotted lines the position of the cover member and its supporting arms when the cover is moved away from its seat and the lipstick is projected.

Fig. 2 is a central longitudinal sectional view.

Fig. 3 is a sectional view in part substantially on line 3—3 of Fig. 2.

Fig. 4 is a transverse sectional view.

20 Fig. 5 is a detail view.

The casing 5 is formed from thin sheet metal drawn into oblong form as shown in the sectional view Fig. 4. A carrier 7 is guided within the casing by the walls thereof. This carrier is of cup shape and is formed of sheet metal. It is operated by a link 8 pivotally connected with the bottom of said cup shaped carrier at 9, the lower end of the link being pivotally connected at 10 to a crank arm 11, which is in the form of a plate reaching from side to side of the casing, and connected at its edges to pintles or journals 12 formed by striking up cup shaped protuberances from the sheet metal arms 13, which normally lie against the flat outer face of the side walls of the casing. These arms are connected at their upper ends to a cover member 14 designed to close the upper open end 15 of the casing when the lipstick is retracted into the casing. This cover member is in the form of a flat plate, and

40 may be an integral portion of the same sheet metal member of which the arms 13 are composed. At the front end of this cover member there is a depending lip 16 which, when the cover is moved into place, will slightly snap over the upper edge 17 of the narrow wall 18 of the casing. At the opposite end of this cover member there is another depending flange 16a which is adapted to contact with the narrow wall 18a opposite the wall 18 first mentioned, to thereby 45 act as a stop in determining the exact position of the cover when this is closing the upper end of the casing.

The journals or pintles 12 find bearings in the opposing wide side walls 19, 19a of the casing at 50 a point near the edges of said wider side walls

19, 19a. The arms 13 taper in width downwardly from the cover member to the journals or pintles 12, and the form of these arms is such that when the cover is closed, the rear edges 13a will substantially align with the rear edge or face of the casing, whereas the front edges 13b of these arms will incline downwardly and rearwardly to the journal portions 12 of the said arms. By offsetting these journals, provision is made for holding a lipstick of considerable length within the casing, because a long crank arm can be employed, owing to the fact that its center of motion is near one edge of the side walls, and the crank arm has ample room within which to describe an arc, such as shown at x of considerable radius. Therefore, the carrier for the lipstick may move from a low position shown in full lines in Fig. 2 to its high position indicated in dotted lines in said figure. The link 8 may be in the form of a wire member having its upper and lower ends bent laterally as indicated at 20, 20a to engage the pivot bearings on the carrier and crank arm member respectively.

25 As before stated, the crank arm member 11 is in the form of a plate, and this is secured to the sheet metal cup shaped journals 12 by riveting. For this purpose a lug indicated at 11a at the upper portion of the crank arm or plate projects through an opening in the bottom of the cup shaped journal 12, and this projecting lug is upset or subjected to a riveting action which will affix it to the sheet metal cup shaped journal. The lipstick carrier member, together with the crank plate and the link all previously assembled are inserted into the sheet metal casing so that the rectangular projections or lugs 11a will align with the bearing openings in the side walls of the casing. Then the cover member with its arms 13 are so applied that the journals 12 will pass through these openings and receive the lugs 11a and thereafter the lugs 11a are upset to firmly connect with said journals, it being understood, of course, that the bottoms of the hollow journals are first perforated to receive said lugs.

30 35 40 45 50 55 The engagement of the locking flange 16, which snaps over the edge 17 of the casing is only sufficient to retain the cover member in place against accidental dislodgment. Slight pressure upon the cover member, however, in the direction in which it moves when swinging to open position, will be sufficient to release the locking flange from its slight engagement with the edge 17 so that the appliance readily may be opened. The cover, together with its side arms and the

cup shaped embossments or journals 12 may be formed in one stamping from thin sheet metal.

The crank arm or plate 11 as shown in Fig. 3 is of special form, providing a narrow portion at 5 11b to receive the pintle of the link, and with a wider portion 11c, the edge of which at 11d may have sliding contact with the inner wall of the casing. This construction tends to brace the thin sheet metal wall of the casing, and this 10 effect is also accentuated by riveting the crank plate to the hollow journals of the arms which carry the cover.

In order to operate the device the cover, together with its carrying arms, is moved from 15 the position shown in full lines in Fig. 2 to the position shown in dotted lines in said figure, or to a position intermediate of these extreme positions, whereupon the journals 12 will turn in their bearings in the side walls of the casing, and 20 thus the crank plate, which is attached to these journals, will be made to move through the arc x of Fig. 2 to move the carrier member of the lipstick upwardly to project the lipstick from the casing, and upon reversal of the movements 25 above described, the lipstick will be withdrawn within the casing and the cover seated in position to close the end of the casing.

It will be noted that not only are the journals 30 offset in relation to the longitudinal center line of the walls which carry them, but these journals bear in the wider side walls of the cross sectional oblong form of the casing, and this arrangement of these journals in connection with the oblong form of the casing in cross section are features 35 contributing to the employment of a long crank arm, so that a lipstick of considerable length may be contained within the holder.

I claim:

1. In a holder for lipsticks and the like, the 40 combination of a casing, a carrier for the lipstick slidable in said casing, a cover member to close the end of the casing, an arm extending from the cover member alongside the outer side of the casing having a journal bearing in and extending 45 through the casing, a crank arm connected with the inner end of the journal, and a link pivotally connected to the crank arm and to the carrier, substantially as described.

2. A lipstick holder having a casing, a carrier 50 therein for the lipstick, a cover to close the end of the casing when the lipstick is retracted, an arm extending from said cover, said arm having a cup shaped journal portion struck out therefrom bearing in the wall of the casing, and means 55 within the casing connected with said cup shaped journal portion for operating the carrier.

3. A lipstick holder comprising a casing, a carrier movable within the casing, a cover for closing the end of the casing, arms extending from said cover and having journals bearing in and extending through the opposite walls of the casing, a crank arm within the casing connected at its opposite edges with the journals and a link connecting the crank arm to the carrier, substantially as described.

4. A lipstick holder comprising a casing, a carrier therein for the lipstick, a cover for the casing, an arm connected with the cover and mounted pivotally on the casing wall at a point to one side 70 of a plane passing lengthwise through the center of the said wall, and a connection between the pivoted end of the arm and the carrier to be operated by the movement of said arm for projecting the lipstick from the casing when the cover 75 is moved to open the casing and for retracting

the lipstick when the cover is moved to close the casing, said connection comprising a crank member connected to the pivoted end of the arm, and a rigid link extending from said crank member to the carrier, and pivotally connected to each of said parts. 5

5. A lipstick holder comprising a casing rectangular in cross section, a carrier for moving the lipstick to project or retract the same relative to said casing, a cover for the end of said casing, an arm extending from the cover along the side of the casing and pivoted to the casing at a point near one edge of said side, and means for moving the carrier connected with the pivoted end of the arm, said means for moving the carrier consisting of a crank member connected to the pivoted end of the arm, and a rigid link extending from said crank member to the carrier, and pivotally connected to each of said parts. 10

6. A lipstick holder comprising a casing, a carrier for the lipstick slidable in the casing, a cover to close the end of the casing, said cover having an extension therefrom journaled in the casing wall with a further extension beyond the journal and disposed to move within the casing, said extensions continuing lengthwise substantially throughout the length of the casing, and a rigid link between the end of said further extension and said carrier to actuate the carrier by swinging movement of said cover and extensions about 30 said journal. 15

7. A lipstick holder according to claim 6 in which said journal is disposed in the casing wall to one side of the longitudinal center line of said wall. 25

8. A lipstick holder according to claim 6 in which said casing is oblong in cross-section, said journal being struck up from said cover extension and seated in an opening adjacent one edge of the wide wall of the casing, and said further extension being rigidly secured to said journal within in said casing. 35

9. A lipstick holder comprising a casing having an open end, a cover having an extension pivoted to the side wall of the casing below the open end and to one side of the longitudinal center line of said wall to move and cover transversely across the open end, said cover having a lip to snap over the edge of the casing remote from the offset pivot, at the end of the transverse closing 50 movement. 40

10. A lipstick holder according to claim 2 in which the cup shaped journal is connected with the operating means within the casing by a lug projecting into an opening in the bottom of the 55 cup shaped journal and riveted in place.

11. A lipstick holder according to claim 3 in which the crank arm consists of a plate like member extending from side wall to side wall of the casing, substantially as described. 60

12. A lipstick holder according to claim 2 in which the means within the casing has a riveted connection with the cup shaped journal, substantially as described. 65

13. A lipstick holder according to claim 2 in which the means within the casing has a riveted connection with the cup shaped journals and also has a bearing against the wall of the casing adjacent the said journal. 70

14. A lipstick holder comprising a casing, a cover member, arms extending from the cover along the outer sides of the casing, and having cup shaped journals struck up from the sheet metal of the arms, and projecting through the opposite walls of the casing, a crank arm within 75

the casing, a lipstick carrier operated from said crank arm, said crank arm consisting of a plate extending from one wall of the casing to the other and riveted at its edges to the said hollow journals, substantially as described.

15. A lipstick holder comprising a sheet metal casing, a sheet metal cover therefor, having in-

tegral arms extending therefrom along opposite sides of the casing with journals struck up from said sheet metal arms extending through bearing openings in the casing, a carrier for the lipstick within the casing, and means for operating the carrier connected to the said journals.
